[57] **CLAIM**

The ornamental design for a mouse house, as shown and described.

DESCRIPTION

FIG. 1 is a perspective view of a mouse house showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and

FIG. 7 is a bottom plan view thereof; and,

FIG. 8 is a perspective view thereof showing the utilization of my design with a mouse being shown in broken lines for illustrative purposes only and forms no part of the claimed design.
